CASTING FLOAT UNIT

Cornelius Albritton, Houston, Tex.

Application December 16, 1955, Serial No. 39,359

Term of patent 14 years

(Cl. D31—4)

Fig. 1 is a side elevational view of a casting float unit, showing my new design;

Fig. 2 is a front elevational view thereof;

Fig. 3 is a top plan view thereof, and

Fig. 4 is a bottom plan view thereof.

The fishing line shown in dotted lines is for purposes of illustration only.

I claim:

The ornamental design for a casting float unit, as shown and described.
